UNITED STATES PATENT OFFICE.

CHARLES EDMOND EVANS, OF SEATTLE, WASHINGTON.

BUNDLING, BINDING, AND TYING MACHINE.

1,324,238.

Specification of Letters Patent.

Patented Dec. 9, 1919.

Application filed October 3, 1916. Serial No. 123,567.

To all whom it may concern:

Be it known that I, CHARLES E. EVANS, a citizen of the United States, and resident of Seattle, county of King, State of Washington, have invented certain new and useful Improvements in Bundling, Binding, and Tying Machines, of which the following is a specification.

This invention relates to improvements in the binding and tying machine described in my co-pending application Serial No. 9,311, filed February 19, 1915.

The objects of the invention are to provide a machine which is entirely automatic in its operation to make one complete cycle of movements after it is started; to provide a yieldable and adjustable means for compressing the bundle prior to being bound with a wire; to provide a tension means for the wire; to provide a tension means for the wire which is entirely independent of the means for compressing the bundle; to provide an arrangement of parts whereby the knot in the wire will be tied at a corner 25 and making equal angles with the adjacent surfaces of the bundle; to provide means for tucking down the knot against one of the surfaces of the bundle; to provide a novel means for releasing the clutch which controls the twister driving mechanism; to provide a novel means for moving one of the twister parts toward and from the other; to provide power means for actuating the bundle support; to provide a machine of the 30 type mentioned in which all of the operative parts are above the floor and accessible; to provide novel and automatic means for moving the bundle support outward after the compressor has acted; and generally to improve this type of machine. Other objects will be apparent from the description taken in connection with the drawings, in which,

Figure 1 is a side elevation of the machine showing the parts in the position occupied 45 just prior to the completion of the tying of the knot;

Fig. 2 is a side elevation illustrating the parts in the position occupied while the bundle is being moved inward to its operative position in the machine;

Fig. 3 is a sectional view taken on the line 3—3 of Fig. 1;

Fig. 4 is a vertical sectional view taken on the line 4—4 of Fig. 3;

Fig. 5 is a front elevation of the machine,

the frame on which the bundle carrier slides being shown in section;

Fig. 6 is an enlarged view showing a front elevation of the mechanism for tripping the clutch;

Fig. 7 is an enlarged view showing the twister in side elevation and the mechanism for tucking down the knot in cross-section;

Fig. 8 is an enlarged view showing the tucking mechanism in plan;

Fig. 9 is a sectional view taken on the line 9—9 of Fig. 8;

Fig. 10 is a perspective view of a bundle showing a wire bound around the same and illustrating the position of the knot after it has been tucked down against the bundle;

Fig. 11 is a top plan view of the bundle support or carrier.

As clearly shown in Figs. 1 and 2, the machine comprises a base 20 having an upstanding post 21. At the top this post carries a bracket 22 securely fastened thereto in any suitable manner, and intermediate of its ends has slidably mounted thereon another bracket 23. This latter bracket has rigidly secured thereto a horizontally arranged frame which may consist of two spaced apart and oppositely arranged channel bars 24. These channel bars carry on their upper edges the ways 25 on which is adapted to slide the bundle support or carrier 26. As clearly shown in Fig. 2, this carrier comprises two vertically extending bars 27 connected by a member 28 U-shaped in plan view and two parallel horizontally extending bars 29 which are arranged to slide on the ways 25. At their forward ends the bars 29 carry depending side pieces 30 which co-operate with the ridges 31 on the ways 25 to securely hold the bundle support in contact with the ways. At the opposite end of the bars 29 similar pieces 32 are secured. This bundle support is adapted to carry a bundle A from the position of the support shown in Fig. 1 inward to position 35 the bundle in the location shown in said figure.

Power means is provided to move this support in both directions, and consists of a cylinder 33 which may be secured to one of the channel bars 24 and has the usual piston and piston rod 34, the latter being connected to a depending lug 35 secured to the bundle support. A valve chest 36 is located at one end of said cylinder and a similar valve chest 37 at the other end. A valve 105 40

rod 38 controls the valves in both of the valve chests, and is adapted to be actuated manually in one direction by a lever 39 and to be operated in the opposite direction by 5 a spring 40 interposed between the valve chest 37 and the connection 41 of the lever 39 to the valve rod. The valve rod carries a collar or block 42 which is located, as shown in Figs. 1 and 2, and has a notch 43 formed on its upper side. This notch is adapted to coöperate with the end of a lever 44 pivotally mounted intermediate of its ends on the valve chest 36. A bar 45 is pivotally mounted between the channel bars 24 10 and projects outside of one of the channel bars to carry an arm 46 which is operatively connected with the lever 44 by means of a link 47. This bar 45 carries an arm 48 located between the channels 24, for a purpose presently to be described.

A compressor is carried by the machine in position to coöperate with the bundle to compress the same after it has been placed in operative position in the machine. In 25 the embodiment herein disclosed this compressor 49 is mounted on a plate 50 carried by the channels 24 at the lower flanges thereof. The plate 50 is hung from these flanges by means of bolts 51 and is spaced 30 from the same by means of thimbles 52 arranged around the bolts. The compressor 49 has a plunger 53 which carries a platform 54 at its upper end, adapted to contact with one side of the bundle. This platform 54 is formed with a groove 55 for the wire which encircles the bundle. The 35 slideable bracket 23 and all the parts carried thereby are counterbalanced by a weight 56 which is hung from a chain 57 passing over 40 wheels 58 being attached to the said bracket at 59. The wheel 58 is arranged to be operated through a worm wheel 60 which in turn may be actuated by a hand wheel 61. The worm and worm wheel provide means 45 for also locking the bracket 23 in any adjusted position because the worm wheel can not drive the worm.

The bracket 22 at the upper end of the post has rigidly secured thereto another 50 bracket 62 which carries the twisting mechanism. This twisting mechanism has been fully described in my said prior application Serial No. 9,311, and as the specific details of the twister form no part of the present 55 invention it will be described only in a general way. The twister consists of two separable parts, each of which is mounted in a corresponding bearing block. One of the twisted parts is mounted in a half bearing 60 block 63 and the other in a complementary block 64. The bearing block 63 is carried by a vertical bar 65 and is mounted to be moved toward and from the bearing block 64. In order to properly register the two 65 blocks when they are together, one of the

blocks 63 carries side plates 66, each having a projecting tongue 67 adapted to be received in a groove 68. At its upper end the twister carries a split gear 69 which is operated by a spur gear 70 non-rotatively 70 mounted on a shaft 71 carried by the bracket 62. This shaft also has mounted thereon to rotate therewith a spur gear 72 which through gear 73 is adapted to actuate a pinion 74 to operate the cutting mechanism. 75 At its upper end said shaft carries a beveled gear 75 which is adapted to be driven by a bevel pinion 76 which is rotatively connected with one member 77 of a friction clutch. The other member 78 of the clutch is rotatively connected to a shaft 79 which is driven by a motor 80 by means of gears 81, 82. The clutch members 77, 78 which may be of any desired type, are urged toward each other by a spring 83. The clutch member 78 is adapted to be moved away from the clutch member 77 against the tension of the spring 83 by means of a clutch yoke 84 rigidly connected with a rock shaft 85. This rock shaft carries a long bent arm 86 90 which, at its upper end, is operatively connected with a longitudinally movable bar 87 arranged over the face of the bevel gear 75. The spring 83 of the clutch normally tends to move this bar 87 downward across the 95 face of said gear. Means is provided, however, for holding the said bar 87 in its upward position so as to compress the spring 83 and disengage the clutch members. This means consists of a plate 88 (see Fig. 6) 100 attached to the end of the bar 87 and formed with a notch 89 adapted to catch against the side of a guide 90. A spring 91 tends to hold said bar 87 with the notch 89 in co-operation with the guide 90. Means which 105 will be presently described is provided for moving the bar 87 laterally to trip the same and permit the spring 83 to engage the clutch member. The mechanism for thus tripping the bar 87 is carried by the movable bearing block 63 and is clearly illustrated in Fig. 6. A bracket or bar 92 is attached to the fixed bearing block 64 and carries the beforementioned guide 90 at its 115 outer end. This guide is rectangular in shape, as shown in Fig. 6, and furnishes a bearing for both the lateral and longitudinal movement of the bar 87. Adjacent this guide 90 the bar 92 is formed with a lug 93 having an adjustable set screw 94 at its 120 outer end. Said bar 92 is also formed with two spaced apart upstanding ears 95 between which is pivotally mounted the dog 96. This dog is of the shape clearly illustrated in the drawings and has one arm 97 125 which is adapted to coöperate with the bar 87 to push the bar laterally and free the notch 89 from the guide 90. All of the above described parts are carried by the stationary bearing member. The movable 130

bearing member 63 carries at its upper end a bracket 98 having two guide wheels 99 and 100 for the wire mounted therein. This bracket has a laterally extending bearing 101 for a vertically movable plunger bar 102. This bar is formed with a collar 103 at its lower end and a spring 104 is interposed between said collar and the bearing 101. At its upper end this plunger is formed 5 with an enlarged head 105 which carries a laterally projecting pin 106 adapted to co-operate with the long arm of the dog 96. The bearing 101 carries a bent lever or latch 107 which has one arm adapted to catch 10 under the head 105 to hold the plunger in position with the spring 104 compressed. The other arm of this bent lever is arranged substantially horizontally and is adapted to co-operate with the set screw 94. In the 15 downward movement of the movable bearing block the end of the plunger 102 strikes against the set screw 108 (see Fig. 1) to thereby compress the spring 104. The spring 109 acting against the latch 107 will force 20 the vertical arm thereof under the head 105 to hold the plunger in its extended upward position. When the said bearing block almost reaches the upward limit of its motion the horizontal arm of the latch 107 will 25 strike the set screw 94, thereby tripping the latch and permitting the spring 104 to move the plunger downward. In this downward movement the pin 106 will strike the long arm of the dog 96 turning the same so that 30 the short arm 97 thereof will push the bar 87 laterally, thereby tripping the same.

The beforementioned bar 65 is guided for vertical movement in the bearings 110 and 111 and carries on one side thereof a rack 40 112. A cylinder 113 is arranged horizontally on the base 20 and has operative connections with the said rack 112, whereby the movable bearing of the twister may be reciprocated in a vertical direction. The cylinder 113 is adapted to be secured to said base in any preferred manner and carries at each end thereof valve chests 114 and 115. A valve rod 116, extends into each of these 45 chests and is adapted to actuate the valve contained therein. A piston rod 117 extends into the cylinder and is adapted to slide in and out of the same. This piston rod is operatively connected to a rack bar 118 which is arranged in parallel relation to the piston rod and is adapted to reciprocate 50 in ways carried on the under side of the cylinder. This rack 118 meshes with a pinion 119 arranged on a horizontal shaft 120 which carries a gear 121 in mesh with the rack 112. It will thus be apparent that as 55 the piston rod 117 is reciprocated the bar 65 carrying part of the twister mechanism will also be reciprocated.

The compressor for the bundle which has 60 been previously described is controlled by a valve 122 which may be secured to the side of the cylinder 113, as shown in Figs. 3 and 4. This valve has a flexible connection 123 to the compressor and exhaust outlet 124 and an inlet 125. This valve is controlled 65 by mechanism operated from the shaft 120. Intermediate of the gears 121 and 119 the shaft 120 has frictionally connected thereto an arm 126. At its outer end this arm 126 is formed with two hooks 127 and 128 which 70 are adapted to co-operate with a pin 129 carried by the two spaced apart bars 130 operatively connected to the valve rod 131 of the valve 122. A bracket 132 is attached to the base 20 and carries two spaced apart 75 pins 133 arranged in the path of movement of the arm 126 and thus acting as stops to limit the movement of the same. In the operation of this valve 122 it will be noted that movement of the rack 118 rotates the 80 shaft 120. This rotation will be frictionally communicated to the arm 126 to revolve the same until it strikes one of the pins 133. However, before the arm thus strikes one 85 of the stop pins, one of the hooks 127 or 128 will have engaged the pin 129 and moved the valve rod 131 to operate the valve 122 and thus control the action of the compressor for the bundle. By this arrangement it 90 will be observed that the compressor is actuated just after the movable twister head has started upward and that it is exhausted to release the bundle just after the said twister head has started downward after the twist 95 has been put in the ends of the wire.

Mechanism is provided for automatically controlling the operation of the cylinder 113. A rod 134 is arranged vertically and parallel to the post 21 in bearings 135 and 136. Said rod carries an arm 137 which is 100 adapted to be actuated by a plate 30 on the bundle support. The rod also carries at its upper end an arm 138 which is adapted to co-operate with a notch 139 formed in a lever 140. This lever is actuated by a spring 141 to normally force the notch 139 down over the arm 138. Thus when the plate 30 on the bundle carrier strikes and rotates the arm 137 thereby turning the rod 134, the arm 138 will be rotated from the position illustrated 110 in Fig. 2, into the position illustrated in Fig. 1 and caught in the notch 139 of the lever 140, thereby securing the rod 134 in its new position. Adjacent the cylinder 113 the rod 134 carries another arm 142 which is connected to the valve rod 116 of the said cylinder. A spring 143 acts on said arm 142 to turn the same in such a direction as to keep the arm and rod 134 in the position illustrated in Fig. 2. The arrangement of parts 115 120 is such that when the rod 134 is rotated from the position of Fig. 2 to the position of Fig. 1, the valve rod 116 will be moved to actuate the valves 114, 115 so that fluid under pressure will be admitted to the cylinder 113 to 130

operate the piston rod 117 to draw the same inward, together with the rack 118, thereby rotating the gears 119 and 121 in such a direction as to elevate the movable part of the twister. When the twister has nearly completed its operation, a lug 144 on the underside of the gear 70 will strike the lever 140, thereby depressing the long arm of the same to raise the notch 139 out of engagement with the arm 138, thereby permitting the spring 143 to rotate the rod 134 and return the parts to the position shown in Fig. 2. This operation of the rod 134 will actuate the valves 114, 115, to return the movable twister head to its lower position, as shown in Fig. 2.

The bracket 22 carries two spaced apart laterally extending arms 145. Each of the arms has rigidly secured thereto a side plate 146 which plates are arranged horizontally and adapted to act as abutments against which the upper side of the bundle is pressed by the compressor. The knot tucking mechanism is carried by these two plates 146. As clearly shown in Figs. 7, 8 and 9, a block 147 having a cylindrical upper surface is secured between the two plates 146 by means of the screws 148. A curved plate 149 is rotatively mounted on the block 147 and has its opposite edges seated in grooves 150 formed in the plates 146. The plate 149 is formed with four lugs one located at each corner thereof. Two lugs 151 carry upwardly extending pins 152 to which are connected springs 153 which tend to rotate the plate in such a direction that the lugs 151 will abut the bar 154. The two lugs 155 arranged opposite to the lugs 151 are adapted to be engaged by mechanism to rotate the plate 149 on the block 147. When thus rotated the edge 156 of the plate will engage the twisted portion of the knot and bend it down against the vertical front face of the bundle so that the knot will assume a position such as shown in Fig. 10. The movable twister head 63 carries at each side thereof a plate 157 which has pivotally mounted at its front end a bent lever 158. One arm 159 of each of these levers is arranged substantially vertically and has its upper end formed with a hook 160 which is adapted to coöperate with a lug 155 on the plate 149. The other arm 161 of the lever is arranged substantially horizontal and has a spring 162 connected therewith and acting to tend to rotate the lever in a clockwise direction as viewed in Fig. 7. A pin 163 limits the movement of the arm 161 so that said arm cannot move above a substantially horizontal position. In view of this description it will be apparent that as the movable twister head moves downward the hooks 160 will engage the lugs 155 thereby pulling around the plate 149 so that the edge 156 thereof will 65 tuck down the knot. After the plate 149

has rotated far enough to so tuck the knot the hooks 160 will slide off the lugs 155 and the springs 162 will return the levers 158 to their normal positions.

As shown in Fig. 7, the relative arrangement of the twister mechanism and the bundle is such that the knot will be tied at one corner of the bundle and the twisted portion thereof makes equal angles with the top and front faces of the bundle, that is, the twisted portion is arranged at substantially 45° with respect to the top horizontal surface of the bundle. Because of this arrangement both of the wires are twisted equally and are bent the same amount. Thus the two wires of the twisted portion are stressed equally in contradistinction to wires which are twisted to form some other angle with the faces of the bundle. For instance, if the twisted portion is horizontally arranged 35 with respect to the top surface of the bundle, that is, if the top wire continues in a horizontal direction in the twisted portion, it will be obvious that the vertical wire has a 90° bend where it begins to be twisted and consequently is stretched that much more.

The wire which is used to bind the bundle extends from a source of supply located where desired to a tension device which may be secured to the floor under the machine, and thence upwardly to the guide rollers 99 and 100. The tension device is shown in Figs. 1 and 2 and comprises a hollow bar or pipe 164 which extends through a hole 165 in the floor 166 and carries at its upper end two spaced apart flat plates 167. A series of three rollers 168, 169, and 170, are mounted on axes secured in the said flat plates. The axes of the top and bottom rollers 168, 170, are parallel and vertically in line. The 105 axis of the intermediate roller 169, however, is arranged at one side vertically of the other two rollers so that a bend is produced in the wire as it passes over these rollers. Furthermore, this central roller 169 has its 110 axis mounted for adjustment laterally whereby the extent of the bent portion of the wire may be varied. At its lower end the bar 164 has secured thereto a collar 171 and just below and in contact with the floor 115 is a loosely mounted collar 172 and intermediate these two collars is a third and loosely mounted collar 173. A spring 174 is interposed between the collars 172 and 173 and a stronger spring 175 is interposed between 120 the collars 173 and 171. Thus it will be apparent that when the wire is drawn upward that because of the bend produced therein by the rollers 168, 169 and 170, the entire tension device will tend to be lifted 125 upward and that this upward tendency will be opposed by the springs 174 and 175. Thus a tension or resistance is provided for the wire and this tension may be varied by adjusting the central roller 169.

In the operation of the machine a bundle is placed on the bundle support when the latter is in the position shown in Fig. 1. The operator then grasps the lever 39 and 5 pushes it to the right, thereby compressing the spring 40 and moving the block 42 to the right so that the lever 44 catches in the notch 43 therein to hold the valve rod 38 in the position indicated in Fig. 2. This movement of the valve rod manipulates the 10 valves to admit fluid pressure so that the piston rod 34 will be drawn into the cylinder thereby moving the bundle support to the right as viewed in Fig. 1. As the said support nears the end of its inward movement, the plate 30 strikes the arm 137, thereby rotating the vertical rod 134 and moving the arm 138 at the top thereof so that it is caught in the notch 139 of the lever 140. 15 This rotation of the rod 134 actuates the arm 142 to move the valve rod 116 of the bottom cylinder 113 to manipulate the valves to admit fluid pressure to actuate the piston rod 117 and rack 118 so that the said parts 20 are moved to the right as viewed in Fig. 2. This right hand movement will rotate the gears 119 and 121 in a direction to actuate the rack 112 and connected bar 65 in an upward direction to move the movable twister part toward the stationary half thereof. 25 The rotation of the shaft 120 turns the arm 126 to thereby catch the hook 128 on the pin 129 to actuate the valve 122 to admit fluid under pressure to the compressor cylinder. It will be observed that this valve 30 is actuated after the shaft 120 has made a fraction of a rotation, that is, this valve is moved so that the compressor will compress the bundle just after the movable twister part has started on its upward movement. 35 Before the bundle moves inward the binding wire extends from the twister downward across the path of the bundle to the tension device. Consequently when the bundle 40 moves inward it pushes the wire ahead of it and thereby arranges the same on substantially the three sides thereof. When the movable portion of the twister head with the wire guide rollers 99 and 100 moves upward it carries with it the wire and thus arranges the same on the front or remaining side of the bundle. The movable twister head in its upward movement strikes the arm 48, thereby tripping the lever 44 out of 45 the notch 43 of the block 42 and permitting the spring 40 to return the valve rod 38 to its original position. This will manipulate the valves of the cylinder 33 so that the piston rod 34, together with the bundle support 50 port will be carried to the left as viewed in Fig. 1 to its original position and ready to receive another bundle. The movable twister part continues on its upward movement and when it has almost completed the 55 same the arm 107 will strike the set screw 60 94 thereby tripping the plunger 102 and actuating the dog 96 to move the bar 87 laterally and allow the spring 83 to engage the clutch members 77 and 78. Thus the rotation of clutch member 78 will be communicated to clutch member 77 and through the gearing to the twister mechanism. When the gear 75 has nearly completed its rotation the lug 144 will strike the lever 140 and trip the other end of said lever from the 70 arm 138, thereby freeing the rod 134. The gear 75 when it has nearly completed its rotation will also carry the lug 176 against the adjustable collar 177 on the bar 87 to move said bar longitudinally to its original position against the tension of spring 83 and to separate the clutch members 77 and 78, thus stopping the operation of the twister mechanism. After the arm 138 at the top of rod 134 is free, the spring 143 will act on the 80 arm 142 to return said rod to its original position and also to actuate valve rod 116 to draw the piston 117 inward and thereby actuate the movable twister part to carry it downward to its low position. Shortly after 85 the beginning of this downward movement, the hooks 160 on the said twister part will engage the tucking mechanism to manipulate the same to tuck down the knot against the bundle. Immediately after this has been 90 accomplished the arm 126 on the shaft 120 will have been rotated to a position so that the valve 122 will be actuated to release the fluid from the compressor thereby freeing 95 the bundle. 100

I have found that the cylinders and co-operating mechanism may be pneumatically actuated very efficiently but of course said cylinders are adapted to be used in connection with any fluid pressure. While I have 105 shown the preferred embodiment of my invention it is obvious that many changes may be made therein without departing from the spirit of my invention.

While a twister comprising two separable parts is illustrated, it is obvious that the organization of the machine herein disclosed is independent of the particular type of twister used, the only requirement being that some movable means be provided to 110 take the wire downward in front and across the path of the bundle and then upward in rear of the same. Hence the term twister part is used to refer to any part of the mechanism which may move downward and 115 upward across the path of the bundle support. 120

Having described the invention what is claimed is:—

1. In a bundle binding and tying machine, 125 in combination, a binder tying mechanism, a binder carrier movable to and from said mechanism, and means for moving said carrier away from said mechanism actuated by the tying movement of the latter. 130

2. In a bundle binding and tying machine, in combination, a binder tying mechanism, a binder carrier movable to and from said mechanism, means for moving said carrier toward the mechanism actuated by the placing of a bundle in position in the machine, and means for moving said carrier away from the mechanism actuated by the tying movement of the latter.
- 10 3. In a machine of the class described, a slidably mounted support for a bundle, fluid pressure means for sliding said support in one direction and automatically actuating means for sliding it in the other direction.
- 15 4. In a bundle binding and tying machine, in combination, a binder tying mechanism, a binder carrier movable to and from said mechanism, and a knot tucking device operated by the movement of said carrier.
- 20 5. In a bundle binding and tying machine, in combination, a binder tying mechanism, a binder carrier movable to and from said mechanism, and means for tucking down the knot tied by said mechanism comprising a slidably mounted member adapted to engage the knot and bend it down against the bundle, said member being actuated by the carrier.
- 25 6. In a machine of the class described, a frame, a support for a bundle mounted on said frame to slide in and out, and power means for moving said support outward controlled by the inward movement of the same.
- 30 7. In a machine of the class described, a frame, a support for a bundle mounted on said frame to slide in and out, fluid pressure means carried by the frame for moving said support inward and automatically outward after a dwell.
- 35 8. In a machine of the class described, a frame, a support for a bundle mounted on said frame to slide in and out, and pneumatic means carried by the frame for reciprocating the support and including valve means manually actuated to move the support inward and automatically actuated by the inward movement to move the support outward.
- 40 9. In a machine of the class described, a slidably mounted support to carry the bundle to operative position in the machine, and fluid pressure means actuated by the movement of the support to compress the bundle.
- 45 10. In a machine of the class described, means for placing a bundle in operative position in the machine and means for thereafter compressing the bundle actuated by the first mentioned means.
- 50 11. In a machine of the class described, means for placing a bundle in operative position in the machine and fluid pressure means for thereafter compressing the bundle actuated by the first mentioned means.
- 55 12. In a machine of the class described, a frame, a bundle support slidably mounted on said frame, a compressor carried by said frame to compress the bundle and means actuated by the movement of the bundle support in one direction for admitting fluid under pressure to said compressor.
- 60 13. In a bundle binding and tying machine, in combination, a binder tying mechanism, a wire carrier movable to and from said mechanism, normally idle power actuated means for operating said mechanism, mechanism for rendering said means operative including a spring pressed plunger carried by said carrier, a latch for holding said plunger under tension adapted to be tripped by the movement of the carrier toward the tying mechanism, and a dog adapted to cooperate with the plunger when tripped.
- 65 14. In a machine of the class described, a two part twister, one part movable to and from the other, and means for so moving the said part comprising a fluid pressure cylinder arranged substantially at right angles to the direction of movement of said part.
- 70 15. In a machine of the class described, a twister having a part slidably mounted and means for sliding said part comprising a power actuated device and gearing between said device and the said part.
- 75 16. In a machine of the class described, a twister having a part slidably mounted, means for sliding said part in one direction actuated by the placing of a bundle in position in the machine.
- 80 17. In a machine of the class described, a twister having a part movable to and from the same, means for moving said part toward the twister actuated by the placing of a bundle in position in the machine.
- 85 18. In a machine of the class described, a twister having a part movable to and from the same, means for moving said part away from the twister actuated by the twisting movement of the twister.
- 90 19. In a machine of the class described, a twister having a part movable to and from the same, means for moving said part toward the twister actuated by the placing of a bundle in position in the machine, and means for moving said part away from the twister actuated by the twisting movement of the twister.
- 95 20. In a bundle binding and tying machine, a binder tying mechanism, a binder carrier movable to and from said mechanism, power means for actuating said mechanism including a clutch, means for holding said clutch disengaged, mechanism for releasing the last mentioned means comprising a spring pressed plunger, a latch for holding said plunger under tension, and means for tripping the latch operated by the movement of the carrier toward the tying mechanism.

21. In a machine of the class described, means for tensioning the wire comprising a hollow slidably mounted member, means carried by said member for resisting movement of a wire through said member, and spring means for opposing movement of the member with the wire. 5 70
22. In a machine of the class described, means for tensioning the wire comprising a 10 slidably mounted member, wheels for the wire carried by said member and arranged to cause a bend in the wire to thereby resist longitudinal movement of the same, and spring means for opposing movement of the member with the wire. 15
23. In a machine of the class described, means for arranging a wire around a bundle, means for tying the same, and means for tucking the knot down beside the wire. 20
24. In a machine of the class described, means for tying a knot in a wire arranged around a bundle and means for tucking the knot down against the bundle. 25
25. In a machine of the class described, means for tying a knot in a wire arranged around a bundle with the knot at a corner of the bundle and projecting at an angle of substantially 45° to the top of the bundle and means for tucking the knot down 30 against the bundle.
26. In a machine of the class described, a two part twister having one part movable to and from the other, and a knot tucking device operated by the movement of said 35 movable twister part.
27. In a machine of the class described, means for tucking down a knot tied in a wire around a bundle comprising a slidably mounted member adapted to engage the 40 knot and bend it down against the bundle.
28. In a machine of the class described, a twister, means for tucking down a knot tied by said twister in a wire around a bundle comprising a slidably mounted member 45 adapted to engage the knot and bend it down against the bundle, said member being actuated by a part of the twister.
29. In a machine of the class described, a two part twister, one part movable to and 50 from the other, normally idle power actuated means for operating said twister, mechanism for rendering said means operative comprising a spring pressed plunger carried by said movable twister part, a latch 55 for holding said plunger under tension adapted to be tripped by the return movement of the movable twister part and a dog adapted to coöperate with the plunger when tripped.
30. In a machine of the class described, a two part twister having one part movable to and from the other part, power means 60 for actuating the same including a clutch means, means for holding said clutch disengaged, and mechanism for releasing the 65 last mentioned means comprising a spring pressed plunger, a latch for holding said plunger under tension and means operated by the return movement of the movable twister part for tripping the latch. 70
31. In a machine of the class described, a vertically slidable twister part, a horizontally arranged fluid pressure engine and gearing connecting said twister part and engine. 75
32. In a machine of the class described, a slidable bundle support, a vertically slid- 80 able twister part, a horizontally arranged fluid pressure engine, gearing connecting said twister part and engine, a valve mechanism controlling the operation of the engine in one direction actuated by the inward movement of the support.
33. In a bundle tying machine, a slidable twister part, a fluid pressure engine, gear- 85 ing connecting said twister part and engine, a fluid actuated compressor for the bundle, a valve for said compressor actuated by a friction connection to the said gearing.
34. In a bundle tying machine, a slidable twister part adapted to carry a wire down 90 across the path of a bundle fed to the machine and then upward in rear of the same, a fluid actuated compressor for the bundle, a valve for the compressor, and means for opening the valve to admit fluid after the twister has completed its downward movement.
35. In a bundle tying machine, a slidable twister part adapted to carry a wire down 100 across the path of a bundle fed to the machine and then upward in rear of the same, a fluid actuated compressor for the bundle, a valve for the compressor, means for opening the valve to admit fluid after the twister part has completed its downward movement, and means for actuating the valve to exhaust the compressor after the twister part 105 has completed its upward movement and has tied the knot in the wire. 110
36. A bundle binding and tying machine, comprising in combination, a bundle carrier for moving a bundle into position in the machine, a bundle compressor, means for actuating said compressor, and means for binding the bundle, said compressor actuating means and binding means controlled by the movement of said carrier. 115
37. A bundle binding and tying machine comprising in combination, automatically 120 actuated means to compress the bundle, bind the bundle, tie and cut the binder and tuck down the knot.
38. A bundle binding and tying machine, including in combination, means for moving 12 a bundle into position in the machine, a binder carrying member movable across the path of the bundle, a tying device, the said member and device being normally on opposite sides of the path of the bundle, means 13

controlled by the movement of the bundle to move the said member from its normal position toward the device, means controlled by the said movement of the member to 5 actuate the device, and automatically actuated means to return said member.

39. A bundle binding and tying machine including in combination, means for moving a bundle into position in the machine, means 10 to compress the bundle, a binder carrying device, means controlled by the movement of the bundle to actuate said device to carry the binder across the path of the bundle in rear thereof, and means controlled by the 15 movement of said device for tying said binder.

40. A bundle binding and tying machine including in combination, means for moving a bundle into position in the machine, means 20 to compress the bundle, a binder carrying device, means controlled by the movement of the bundle to actuate said device to carry the binder across the path of the bundle in rear thereof, means controlled by the 25 movement of said device for tying said binder, and means for tucking in the knot.

41. A bundle binding and tying machine including in combination, means to move a bundle into position in the machine, means 30 to compress the bundle, mechanism to carry a binder across the path of the bundle in advance thereof and thereafter across said path in rear of the bundle, means for tying the binder controlled by the movement of said mechanism in rear of the bundle, and means for tucking in the knot; the movement of said mechanism to carry the binder in advance of the bundle being controlled by said tying means.

40 42. A bundle binding and tying machine including in combination, means to move a bundle into position in the machine, means to compress the bundle, mechanism to carry a binder across the path of the bundle in advance thereof and thereafter across said path in rear of the bundle, means for tying the binder controlled by the movement of said mechanism in rear of the bundle, and means for tucking in the knot, the movement of said mechanism to carry the binder in advance of the bundle being controlled by said tying means, and means controlled by movement of said mechanism for releasing the compressing means.

55 43. A bundle binding and tying machine including in combination means for moving the bundle into position in the machine,

means to compress the bundle, a binder carrying device, means controlled by movement of the bundle to actuate said device to 60 carry the binder across the path of the bundle in rear thereof, and means controlled by the movement of said device for returning said bundle moving means.

44. A bundle binding and tying machine 65 including in combination, a bundle compressor, a bundle carrier to deliver the bundle to the compressor, and means controlled by the movement of the bundle for actuating the compressor and returning the 70 bundle carrier.

45. A bundle binding and tying machine including in combination, a bundle compressor; a bundle carrier to deliver the bundle to the compressor, means controlled 75 by the movement of the bundle for actuating the compressor, means to arrange a binder around the bundle, and means controlled by movement of said last mentioned means for returning the bundle carrier. 80

46. A binding and tying machine, including in combination, a binder tying device, a knot tucking device independent of the tying device, and means for actuating the tucking device. 85

47. A binding and tying machine, including in combination, a binder tying device, arranged to tie the binder at a corner of the bundle, an abutment for one side of the bundle, means for compressing the bundle 90 against said abutment, a knot tucking device independent of said tying device carried by said abutment, and means for actuating the tucking device.

48. A binding and tying machine, including in combination, means for arranging a binder around the bundle, means for tying said binder and means for tucking down the knot actuated by said first means. 95

49. A binding and tying machine, including in combination, means for carrying a binder across the path of the bundle, means for tying the binder, and means for tucking down the knot actuated by said first means. 100

50. A binding and tying machine, including in combination, means for carrying a binder across the path of the bundle, means for tying the binder, means for tucking down the knot including a yieldable hook on said first means, and a projection on said 105 tucking means in the path of said hook. 110

In testimony whereof I affix my signature.

CHARLES EDMOND EVANS.
